UNITED STATES PATENT OFFICE.

LOUIS H. HARTMAN, OF TOLEDO, OHIO, ASSIGNOR, BY MESNE ASSIGNMENTS, TO ST. REGIS PAPER COMPANY, OF NEW YORK, N. Y., A CORPORATION OF NEW YORK.

APPARATUS FOR VALVING BAGS.

Application filed February 9, 1928. Serial No. 252,971.

This invention relates to apparatus for tucking in the corners of bags to form valves. The general purpose and operation of the device is similar to that disclosed in the patent to Bates, Dorr and Dansker, No. 1,623,228, issued April 5, 1927. This invention relates particularly to the mounting and operation of the several devices for forming the valve, particularly the tucking-in finger.

10 The particular features of the improved construction will more fully appear as the description proceeds, and will be pointed out in the appended claims.

Referring to the accompanying drawings forming a part of this specification, Figure 1 is a plan view, with parts broken away, of one form of apparatus embodying my invention; Fig. 2 is a side elevation of the apparatus disclosed in Fig. 1; Fig. 3 is an end view, and partly in section, of the apparatus shown in Figs. 1 and 2, looking at the right end of the apparatus shown in those figures; Figs. 4 and 5 are sections on lines 4-4 and 5-5, respectively, of Fig. 2; Fig. 6 is a horizontal section substantially on the line 6-6 of Fig. 2; Fig. 7 is an enlarged somewhat diagrammatic view showing the operation of the spreading wings; Fig. 8 is a section through the clamping jaws substantially on the line 8-8 of Fig. 1.

The main operating parts of the valve-forming device consist of clamping jaws 10, which are adapted to seize the edge of a bag near one end thereof where the valve is to be formed, spreading wings 11, which are adapted to enter the gusset-fold of a bag between the clamp and the end of the bag to spread apart the gusset-fold, and tucking finger 12, which is adapted to tuck in the corner of the bag after the gusset-fold has been spread apart.

Clamping jaws 10 are mounted upon arms 13 fulcrumed at 14 and having rear extensions 15 connected by a spring 16 which normally holds the clamping members apart. Rollers 17 mounted in arms 13 are adapted to be contacted by cam members 18 on a slide rod 19, thus forcing apart the rear ends of members 13 against the tension of spring 16 and bringing the clamping members 10 against the opposite sides of a bag placed therebetween.

Slide 19 is mounted in keepers 20 within a casing 21. A lever 22 has one end forked

to enclose a roller 23 adjustably mounted upon slide 19. Lever 22 is mounted upon a stationary fulcrum 24 and has at its other end a cam roller 25 running in a cam groove 26 in a cam wheel 27 on power shaft 28.

The clamping jaws may be formed in any suitable way, but in the construction shown in detail in Fig. 8, the members 29 which actually contact the bag are mounted on the ends of screws 30 which may be locked in adjusted positions on arms 13 by means of lock nuts 31. By this construction the distance apart of the jaws of the clamps may be accurately adjusted. Spreading wings 11 are mounted like hinges upon a pin 32. Links 33 connect the carriers of spreading wings 11 with a slide 34, which slides in casing 21 parallel with slide 19. A lever 35 has one end forked to receive a roller 36 adjustably mounted on slide 34. Lever 35 is fulcrumed at 37 and has a cam roller 38 at its other end working in a cam groove 39 in a cam wheel 40 on power shaft 28. Another cam wheel 41 may be made in a separate member and bolted to cam wheel 40, or may be made integral therewith. A cam groove 42 in cam wheel 41 operates a roller 43 on the end of a lever 44 fulcrumed at 45. The other end of lever 44 is forked to receive a roller 46 adjustably mounted upon a slide 47 which slides longitudinally of casing 21 parallel with slides 19 and 34. The end of slide 47 is provided with teeth 48, which mesh with a pinion 49 on a stub shaft 50. Stub shaft 50 is mounted in a bracket 51 and bears upon its upper end a crank arm 52. Tucking finger 12 is attached to the outer end of crank arm 52 by means of screws 53, or in any other suitable way.

Tucking finger 12 has an end 54 bent at such an angle as to lie normally parallel with the direction of movement of slides 19, 34 and 47, which is parallel with the edge of a bag in position to be valved by the apparatus. As will be seen from Figs. 1 and 6, the axis of shaft 50 is directly in line with the edge of end 54 of tucking finger 12. The end 54 is rounded at 55 and rests movably, but snugly, between wear plates 56 in the end of pin 32.

Rollers 23, 36 and 46 may be adjustably mounted on their respective slides in any convenient manner. In the drawings, roller 46 is clearly indicated on Fig. 2 as being

mounted upon a block 58 slidably lengthwise of slide 47. The block may be fastened in adjustable position on the slide by means of set screw 59. Roller 36 is similarly mounted upon a block 60 held in adjusted position on slide 34 by screws 61, and roller 23 is similarly mounted upon a block 62 adjustable upon slide 19.

When slide 47 is operated, crank 52 is moved from its full line position to its dotted line position in Fig. 6 carrying Fig. 12 from its full line position to its dotted line position in that figure. It will be readily seen that the finger moves about the axial line of stub shaft 50 so that it may turn the fabric of the bag directly at right angles about a single point. It will be further understood that if the finger were mounted to turn about a pivot passing through end 54 of the finger, it would be impossible to have the axis about which it turned directly against the edge of the bag. For this reason it would be impossible to make as accurate a fold in the bag as is made by the tucking finger mounted in the manner herein disclosed.

By sliding the end of tucking finger 54 within a groove in the end of pin 32, it is possible to have this free end of the tucking finger held securely in one plane while at the same time it is allowed to move about an axis in line with its outer edge.

By operating each one of the three devices of the valver, that is, the clamping members, the spreading wings, and the tucking finger, by separately adjustable members and by cams which are rotated by the same shaft, but may be suitably arranged with respect to each other, it is possible to separately adjust the operation of any one of these devices so as to time them in the exact relation to the timing of the other devices which is found to be most desirable. Furthermore, in the construction disclosed herein, any one of the three devices may be readily removed and replaced by another without interfering with the other two devices, and any one of the parts may be readjusted to take up wear, or for any other purpose, at any time without disturbing the adjustment of the other two. Each device is required to stand the strain of performing its own operation only, and is not subjected to any strain from the operation of the other devices.

It will be readily understood that various changes may be made in the construction described without departing from the scope of the invention as set forth in the appended claims.

What I claim is:

60 1. In apparatus for forming valves in valve bags, comprising a tucking finger for folding in one corner of the bag, means for holding the finger normally parallel with one side of the bag, with its edge adjacent to the bag and substantially in contact with

the bag, and means for swinging the finger about an axis passing through its edge in contact with the bag.

2. In apparatus for folding valves in valve bags, a tucking finger having one edge normally parallel with an edge of the bag near one end thereof, a pivot at one side of the plane of the bag and having its axis perpendicular to the plane of the bag at the edge of the tucking finger, means supporting the finger upon said pivot, and means for oscillating the finger about said axis to tuck in one corner of the bag.

3. In apparatus for folding valves in valve bags, a pivot having its axis normal to the plane of the bag at one edge of said bag and at the point about which the corner of the bag is to be folded in tucking in the valve, a crank arm extending outward from the pivot and then into the plane of the bag, and a finger mounted upon the end of said crank and having an operating surface normally parallel with the side of the bag and passing through the axial line of said pivot, and means for oscillating said pivot, crank arm and finger to tuck in the corner of a bag to form the valve.

4. A construction in accordance with claim 3, wherein the end of the finger adjacent the axial line of the pivot is slidably mounted in a guiding slotted member adjacent the edge of the bag.

5. In apparatus for forming valves in valve bags, comprising a clamping member for clamping a bellows-folded edge of a bag near one corner thereof, spreading members for entering the bellows-fold of the bag and spreading it apart between the clamping members and the corner of the bag and a tucking finger for tucking in the end of the spread-apart end of the bellows-fold, means for moving the tucking finger about an axis perpendicular to the edge of the bag, and a pivot for the spreading members perpendicular to the side of the bag and to the axial line about which the finger is moved, there being a slot in the end of said pivot member for receiving one end of the finger.

6. In apparatus for folding a valve in a valve bag, a casing adapted to lie along one side of a bag to be valved, clamping members adapted to clamp the side of the bag adjacent one corner thereof, spreading members adapted to enter the gusset-fold of a bag to be valved and spread the fold apart between the clamping members and the corner of the bag, a finger adapted to fold in the spread-apart end of the gusset-fold, three slides supported by said casing and operating respectively the clamps, the spreading member and the finger, and separate means for operating each of said slides.

7. Apparatus in accordance with claim 6, in which the means for operating each of the slides comprises an adjustable device on

the slide, a lever having one end connected to said device and a cam for oscillating said lever.

8. Apparatus in accordance with claim 6,
5 in which the means for operating each of said slides comprises a device adjustably mounted on the slide, a lever having one end

connected with said device and a cam for operating the lever, and there being a power shaft upon which the cams for the three ¹⁰ levers for the three slides are fixed.

In testimony whereof I have hereunto signed my name to this specification.

LOUIS H. HARTMAN.
